UNITED STATES PATENT OFFICE.

JOSEPH ZUBATY, OF FLINT, MICHIGAN, ASSIGNOR TO A C SPARK PLUG COMPANY, OF FLINT, MICHIGAN, A COMPANY OF MICHIGAN.

LIGHTING MEANS FOR INSTRUMENT ASSEMBLIES.

Application filed July 30, 1925. Serial No. 47,058.

The object of this invention is to provide a lighting means for an instrument assembly for automobiles which will give a soft indirect illumination of the indicating means or dials of the instruments in a manner to prevent glare and will also preferably afford a diffused lighting of a portion of the car such as the floor adjacent the driver's seat. This latter arrangement provides for the illumination of the usual transmission lock, a point where lighting is much needed and which has been neglected in the past.

Specifically, my illuminating means has taken the form of a reflector disposed adjacent one of the instruments or between a plurality of instruments and provided with a customary light bulb. The specific form of reflector which I have preferred to use is so shaped as to project light upon the instrument dials through apertures in the casings thereof, and also to project a portion of the light upon the floor of the car for general illumination. If desired, the light supplied to the instruments may be tinted by passing it through a suitably colored transparent medium.

I have also preferably so designed my assembly as to permit the removal of the instruments without disturbing the lighting means, or if the lighting means requires repair or adjustment this may be done without disturbing the mounting of the instruments.

Figure 1 is a front elevation of my improved assembly;

Figure 2 is a rear elevation thereof;

Figure 3 is a section on the line 3—3 of Figure 2, parts being broken away;

Figure 4 is a section on line 4—4 of Figure 1;

Figure 5 is a rear elevation of a modified form;

Figure 6 is a section on line 6—6 of Figure 5; and

Figure 7 is a rear elevation of a modified form.

An instrument panel of the type used on automobiles is indicated by the reference character 2. Obviously the panel may be of the well-known detachable type especially adapted for bench assembly of the instruments, or may be a permanent part of the body structure. It may also be of any desired shape. I have shown mounted upon it in

any preferred manner the usual dash instruments, such as a speedometer 4, control switches 6, clock 8, oil gage 10, gasoline gage 11, and ammeter 12, the last four of which are preferably mounted in a single casing 14 having a cover 15. The casing of the speedometer is indicated by the character 16 and its cover by the reference character 17. The instruments are preferably removably secured to the instrument panel by any preferred clamping means, an example of which is shown at 18.

Each of the covers 15 and 17 is provided with the usual aperture 22, 23, ordinarily glass covered, which is framed in an opening in the instrument panel in the usual manner. Over these apertures and beneath the usual glass are arranged cover plates 24 and 26 having openings, as shown, for the display of the instrument dials indicated at 28. The cover plate 24 also carries upon its face the dial 30 for the clock 8. The cover plates may be secured in position in the covers by means of a plurality of clamping members or by annular clamping plates in the manner indicated at 25 Figure 4. At the rear of the instrument panel the casings 14 and 16 are provided with apertures 32 and 34, the apertures preferably being provided with covers 33 and 35 respectively of transparent material to prevent the admission of dust. The apertures are so located as to permit the projection of light therethrough for the illumination of the dials at the rear of the cover plates 24 and 26. The cover plate 24 is also slotted as at 31 adjacent the dial 30 to permit the passage of light for the illumination thereof. In order to prevent too great loss of light by absorption I have found it preferable to so treat the rear of the cover plates as well as the other parts of the interior of the instrument as to be efficient reflectors, either by painting them white, silvering them, or the like.

My illuminating means is shown at 36 and preferably comprises a reflector in the form of a casing 38 secured to the instrument panel between the casings 14 and 16 and independently thereof and having portions 40 conforming in shape and in size to the apertures 32 and 34 and fitting closely thereagainst. The casing 38 is also provided with a portion 42 projecting between the casings 14 and 16 through which light is thrown upon the floor of the automobile. A light

bulb 44 is secured in the casing or reflector 38 in any suitable manner.

It will now be apparent that part of the light from the bulb 44 will be projected by the reflector through the apertures 32 and 34 into the casings 14 and 16 to the rear of the cover plates 24 and 26 and will illuminate the dials, and in the case of the casing 14 some of the light will be emitted through the slot 31 adjacent the dial 30 and thus illuminate the latter. Another portion of the light will be projected through the part 42 of the reflector downwardly upon the sides of the instruments and the floor of the vehicle. To assist in the dispersion of this light and to avoid loss of light, the sides of the instrument casings may be treated to form reflecting surfaces.

By the use of colored media at 33 and 35 a tinted light may be thrown on the instruments. The color may be chosen either with a view to producing greater visibility or a more æsthetic appearance. If desired a transparent member 46, colored or uncolored, may be provided at the opening 42.

It will also be apparent that with the construction described the instruments are individually removable without disturbing the lighting means.

I have shown at 48 a conventional dash light mounted upon the face of the panel which may be used to supplement the indirect illumination just described.

In the modification shown in Figures 5 and 6 I have illustrated a plurality of instruments 50, 52 and 54 having the usual display apertures, not shown, and being also provided with apertures 56, 58 and 60, respectively, preferably having transparent coverings as before to prevent the admission of dust. Cooperating with these apertures is a light distributing device, shown at 62 and comprising an arrangement of channels one of which, numbered 64, conducts light to the aperture 56, another, numbered 66, to the aperture 58, and another, numbered 68, to the aperture 60. At its central point the light distributing device carries a light bulb 61 mounted in any preferred manner. The channels 64 and 68 have openings 70 through which light is projected downwardly for general illumination, as in the preferred form. These openings may be covered with transparent media, if desired. As in the preceding form the transparent covers may, in each instance, be colored or uncolored, as desired. It is of course desirable, as in the preferred form, that the surfaces upon which the light rays are thrown in their passage to the points which it is desired to illuminate be painted white or otherwise converted into good reflecting surfaces in order to prevent losses by absorption.

With the construction shown in Figures 5 and 6 a part of the light passing through

the apertures 56 and 60 consists of direct rays from the bulb 61. The remaining portion consists of light reflected from the walls of the channels or tunnels 64 and 68. A large proportion of the reflected light reaches the apertures in the instrument housings only after multiple reflection from wall to wall of the tunnels. The purpose of this is to obviate shadows and obtain very uniform and diffused lighting of the instrument dials since the light comes from any directions instead of from one.

The form shown in Figure 7 differs from the preceding forms in that all of the instruments are mounted in a single casing 72. The lighting means, consisting of a reflector provided with a bulb 76 is mounted at one side thereof, and illuminates the instruments in the same manner as before. The reflector is apertured as at 78, forming a window for the projection of a portion of the light upon the floor. This aperture may be provided with a transparent cover to exclude dust.

In the actual design of an instrument assembly embodying the above features it is essential that certain proportions of parts be observed. Thus referring again to Figure 3, the face plate 24 should be spaced a comparatively large distance from the dial indicated at 11' so that a considerable area of the rear face thereof will be in position to throw light upon the dial. Also, the area of the dial should be sufficiently greater than the area of the opening as at 99 in the face plate so that the instrument assembly will present a finished appearance when viewed from any angle. To further improve the appearance of the assembly the inturned edges 101 of the face plate defining the opening for the display of the dial should be spaced a comparatively small distance from the dial.

I claim:

1. In an automobile, the combination of an instrument panel, an instrument assembly removably mounted thereon comprising a casing having an instrument therein provided with indicating means, said casing having an aperture therein, a cover plate for said aperture provided with an opening, said indicating means being arranged for display through said opening, and lighting means for the illumination of said indicating means, said casing being provided with a second aperture at the rear of said cover plate for the passage of light from the lighting means to the indicating means for the indirect illumination of the latter.

2. The structure as defined by claim 1, said lighting means comprising a reflector independently mounted upon the instrument panel and shaped to direct light into said second named aperture, and a source of light associated with said reflector.

3. In an automobile, an instrument panel,

- a plurality of instruments secured to said panel having indicating means for display upon said panel and comprising casings, portions of which project rearwardly of the panel, apertures in said portions of the casings, a reflector mounted upon the rear of said panel and between said instruments, a source of light within the reflector, portions of said reflector fitting the apertures 10 in the casings for the projection of light therethrough for the illumination of the instruments, said reflector also being shaped to provide an opening between the apertures in the rearwardly projecting portions of the 15 casings for the projection of light downwardly between the instrument casings.

4. An instrument assembly comprising a casing, an instrument in the casing, said casing having an opening therein, a cover 20 plate for said opening, a dial carried by said cover plate for cooperation with said instrument, said cover plate being apertured adjacent said dial, and illuminating means arranged to project light through said aperture from the rear of said cover plate for 25 the illumination of said dial.

5. An instrument assembly comprising a casing, a plurality of instruments in the casing, indicating means for one of said 30 instruments, said casing having an opening for the display of said indicating means, a cover plate for the opening, said plate being apertured for the inspection of said indicating means, a dial carried by said cover 35 plate for cooperation with another of said instruments, said cover plate being provided with a slot adjacent said dial, and means for illuminating the indicating means from the rear of said cover plate, said illuminating 40 means being adapted to project light through the slot for the illumination of the dial carried by the cover plate.

6. The combination of an instrument having indicating means, said instrument including a casing having an aperture for the 45 display of the indicating means, said casing being provided with a second aperture for the projection of light from without the casing upon the indicating means for rendering 50 the latter visible through said inspection aperture, and a source of light without the casing and mounted independently of the casing and adapted to project light through the second-named aperture.

55 7. The combination of an instrument panel, an instrument mounted on the panel, said instrument comprising indicating means and a casing provided with an aperture for the display of the indicating means, and 60 with a second aperture exposed at the rear of the panel, and a source of light concealed by the panel and arranged to project light through the second-named aperture to render the indicating means visible through 65 said first-named aperture.

8. The combination of an instrument panel, an instrument mounted thereon, said instrument comprising indicating means and a casing, said casing being provided with an aperture for the display of the indicating 70 means and with another aperture exposed at the rear of the panel, transparent media covering said apertures and preventing the entrance of dust into the casing, and a source of light mounted independently of the instrument and concealed by the panel and arranged to project light through the second-named aperture for the indirect illumination of the indicating means.

9. The combination of an instrument 80 panel, a plurality of instruments mounted thereon, each of said instruments comprising indicating means and a casing having an aperture for the display of the indicating means and a second aperture positioned 85 at the rear of the panel for the projection of light upon the indicating means, a light source concealed by the panel, said second-named apertures being arranged to permit passage of light from the source there- 90 through to the indicating means to render the latter visible when viewed through the first-named apertures.

10. The combination of an instrument having indicating means, a casing for the instrument having an aperture for the display of the indicating means, said casing being provided with a second aperture for the projection of light from without the casing 100 upon the indicating means for rendering the latter visible through said inspection aperture, a source of light, and a reflector for conducting light from the source to the second-named aperture, said reflector being of elongated tunnel form causing multiple reflection of light from wall to wall producing uniform and diffused illumination of the 105 indicating means.

11. The combination of an instrument panel, a plurality of instruments mounted 110 thereon, each of said instruments comprising indicating means and a casing having an aperture for the display of the indicating means and a second aperture positioned at the rear of the panel for the projection of light upon the indicating means, a light source concealed by the panel, said second-named apertures being arranged to permit 115 passage of light from the source there- through to the indicating means to render the latter visible when viewed through the first-named apertures, and reflectors for conducting light from the source to the second-named apertures, said reflectors being of 120 elongated tunnel form causing multiple reflection of light from wall to wall producing uniform and diffused illumination of the indicating means.

12. In an automobile, the combination of 125 an instrument panel, an instrument mounted 130

1
thereon, said instrument comprising indicating means and a casing, said casing being provided with an aperture for the display of the indicating means and with another aperture exposed at the rear of the panel, transparent media covering said apertures and preventing the entrance of dust into the casing, a source of light mounted independently of the instrument and concealed by the panel and arranged to project light through the second-named aperture for the indirect illumination of the indicating means, a reflector for conducting light from the source to the second-named aperture, and an aperture in said reflector for directing light to other parts of the vehicle.

13. The combination of an instrument panel, an instrument mounted on the panel, said instrument comprising indicating means and a casing, said casing being provided with an aperture for the display of the indicating means and with another aperture exposed at the rear of the panel, a transparent cover for said second-named aperture preventing the entrance of dust into the casing, a source of light mounted independently of the instrument and concealed by the panel and arranged to project light through the second-named aperture for the indirect illumination of the indicating means, and a reflector associated with the light source and arranged to direct reflected light through said second-named aperture producing dif-

fused illumination of the indicating means.

14. The combination of an instrument panel, a plurality of instruments mounted on the panel, said instruments each comprising indicating means and a casing, each casing having an aperture for the display of the indicating means and a second aperture positioned for the projection of light upon the indicating means, a light source, and a reflector associated with the light source and cooperating with each of said second-named apertures for producing diffused illumination of the instruments.

15. The combination of an instrument panel, a plurality of instruments mounted thereon, each of said instruments comprising indicating means and a casing having an aperture for the display of the indicating means and a second aperture positioned at the rear of the panel for the projection of light upon the indicating means, a light source concealed by the panel, said second-named apertures being arranged to permit passage of light from the source therethrough to the indicating means to render the latter visible when viewed through the first named apertures, and a reflector common to said second named apertures and said light source for effecting soft and diffused illumination of the indicating means.

In testimony whereof I affix my signature.

JOSEPH ZUBATY.
